DESIGN FOR A GREENHOUSE

Ray C. Hansen, Portland, Oreg., assignor to M
and M Wood Working Company, Portland,
Oreg., a corporation of Oregon

Application October 12, 1938, Serial No. 80,406

Term of patent 14 years

To all whom it may concern:

Be it known that I, Ray C. Hansen, a citizen of the United States and a resident of Portland,
in the county of Multnomah, State of Oregon,
have invented a new, original, and ornamental Design for a Greenhouse, of which the following is a specification, reference being had to the accompanying drawing forming a part thereof.

house showing my new design.

I claim:

The ornamental design for a greenhouse, substantially as shown.

RAY C. HANSEN.
